UNITED STATES PATENT OFFICE.

HORACE H. DOLL AND MERRILL H. BOSTIAN, OF CAMDEN, NEW JERSEY.

AUTOMATIC SWITCH.

SPECIFICATION forming part of Letters Patent No. 703,561, dated July 1, 1902.

Application filed March 27, 1901. Serial No. 53,146. (No model.)

To all whom it may concern:

Be it known that we, HORACE H. DOLL and MERRILL H. BOSTIAN, citizens of the United States, and residents of Camden, in the county 5 of Camden and State of New Jersey, have invented certain new and useful Improvements in Automatic Switches, of which the following is a full, clear, and exact specification, reference being had to the accompanying 10 drawings, forming a part hereof.

Our invention relates to certain improvements in railway-switches of that class designed to be operated from an approaching car; and its object is to provide a new and 15 improved switch of this character in which the switch may be operated from the car and locked in position during the travel of the car or cars over the switch and then automatically returned to the original position 20 after the car or cars have left the same, as more fully set forth hereinafter.

In the accompanying drawings, Figure 1 is a plan view of an automatic switch constructed and arranged in accordance with our invention. Fig. 2 is a side elevation of a portion 25 of the same. Fig. 3 is a detail of a hand operating-lever which may be employed to operate the switch. Fig. 4 is an elevation of a car-truck carrying switch-operating shoes 30 in accordance with the invention, and Fig. 5 is a perspective view of the switch-operating shoes detached.

In the drawings is illustrated an open main track A', the rails of a side leading to the 35 switch. On the ties, at the sides of the rails, are secured plates a' a² a³ a⁴, arranged in pairs, the plates a' a² being outside the siding-rails. On these plates respectively are pivoted levers C' C² C³ C⁴, having curved faces close to the 40 outer edges of the rails for contact with the switching-shoes B, carried by the trucks C. The trucks C, or, as the case may be, the forward end of the engine or the platform of the car, are provided with shoes B, having shanks 45 a, guided in suitable vertical bearings on the cars and normally held in an elevated position by springs a⁵ or any equivalent means, their depression to operative position being effected by any engine-driver or motorman. 50 The needle or switch points B' B² are of the usual type, and both are secured to a transverse bar N', the movement of which

clears either the main or the siding rails. This bar N' is secured at one end to a T-shaped lever K, fulcrumed at the center of 55 its three arms to a base-plate x. The main arm k of this lever is connected to a lever J, which may be moved by hand to shift the switch, the lever being locked by stops j' on a quadrant j in either the open or closed position, as shown in Fig. 3. This lever K is also operated upon by a spring k', so as to keep it in the position shown in Fig. 1, the spring being guided by a bolt l, connected to a bracket N on the base-plate x, said bracket 60 being adjustable on said base-plate to increase or decrease the pressure of the spring.

Extending from the lever C' to the arm k of lever K are a series of levers and connecting-bars, (indicated by the letters D', E', F', 70 G', H', I', H², and I²), the arrangement being such that when the shoe B on the oncurving car presses against the lever C' the lever K will be moved against the action of the spring L and move the bar N' to open the 75 switch to the siding-rails. The lever C² is connected to the lever K through the medium of the lever D² and its connecting-bars for a similar purpose as the lever C'.

On the switch-rails the lever C³ is connected 80 to lever K by levers and connecting-bars D³, E³, F³, and G² to effect the movement of the switch, and lever C⁴ is likewise connected to said lever K by levers and bars D⁴ E² F², the latter being connected to the bar G². 85

The result of the various connections is such that when a car, with its shoe B depressed, approaches one or other of the levers C' C² C³ C⁴ the lever K will be moved from the position shown in Fig. 1 to change the 90 switch-points B' B² and open communication between the main line and the siding.

The switch-bar N' is secured to or formed integral with a bar N², having its outer end guided in a frame R, provided with openings 95 for the reception of locking-pins s, which may enter into a suitable opening in the bar N² and lock the same to keep the switch either open or closed during the passage of a car or cars. This locking-rail U extends parallel with and outside of the curved rail of the siding from points opposite the levers C' C⁴, its upper edge being a trifle above the level of the load-rail, so that it may be acted upon by 100

the wheels. The rail U has pins or trunnions W, adapted to coact with curved slots w in plates V, secured to permanent bases, and this rail is connected by a lug T, rod O², bell-crank lever P, and rod O' to one arm of the main operating-lever K, the connection being such that the locking-rail is moved backward or forward at each movement of the switch-lever. To lugs V' V² on the locking-rail are pivoted arms Z' Z², respectively, forming universal joints for the attachment of the spring locking-pins s, the movement of the rail withdrawing one or other of such pins from engagement with the bar N².

15 The operation of the device is as follows: If the parts be in the normal position, as in Fig. 1, with the main-line rails open and a car or train approaching on the main line wishes to take the siding or a car or train on the siding wishes to take the main line, the engineer or motorman depresses the shoe B. This shoe then comes into contact with one or other of the levers C', C², C³, or C⁴ and through the intervening levers previously described operates on lever K and switch-bar N' to open the switch to the siding. This movement also shifts the locking-rail and causes one or other of the pins s to lock the switch in the position to which it is adjusted.

20 The car or train then enters upon and depresses the locking-rail, holding the same in its locking position until the last wheel of the car or train has left it. The spring L then acts to cause all the parts to reassume

25 their normal positions, leaving the main line again open for traffic.

The device is admirably adapted for street-railways and especially electrical railways in rural districts where single lines are used and 40 cars must pass each other on sidings, but it may be used in any capacity on street, electric, or steam railways, as desired.

The invention may be modified in a variety

of ways and the number and arrangement of levers and operating devices increased or diminished without departing from our invention. 45

Having thus described our invention, what we claim, and desire to secure by Letters Patent, is—

50 1. In an automatic switch, the combination with the main and siding rails, and a movable locking-rail on one of said siding-rails, of a lever, a switch-bar pivotally connected thereto, and spring-actuated pins arranged on opposite sides of the switch-bar, the pins being also pivoted to the said locking-bar to permit of a longitudinal movement of the same and to lock said bar, and means for actuating said lever whereby the switch may be shifted and 60 locked in its shifted position, substantially as specified.

55 2. In an automatic switch, the combination with the main and siding rails, of a lever, a switch-bar pivotally connected to said lever, and actuated thereby, locking-apertures in said bar, a locking-rail mounted upon one of the siding-rails and having an operating connection with said spring-actuated lever, locking-pins pivotally connected with said locking-rail and located upon opposite sides of the switch-bar, said pins designed to enter the locking-apertures of said bar to lock the same and means for operating said lever whereby the switch may be shifted and locked 70 in its shifted position, substantially as described.

75 In testimony whereof we have signed this specification in the presence of two subscribing witnesses.

HORACE H. DOLL. [L. S.]
MERRILL H. BOSTIAN. [L. S.]
